UNITED STATES PATENT OFFICE

2,422,651

MULTIPLE LOOP CONTROL

Maurice D. Ayers, Pittsburgh, Pa., assignor to
Carnegie-Illinois Steel Corporation, a corpora-
tion of New Jersey

Application December 31, 1943, Serial No. 516,583

16 Claims. (Cl. 271—2.3)

1

This invention relates to a multiple loop control for a continuous processing line or the like. In continuous strip processing lines, such as electrotinning, pickling, and the like, one coil of strip must be welded or otherwise fastened to a succeeding coil and during this welding operation the tail end of the leading strip must be stationary. In order to keep the strip moving through the processing equipment during welding it is necessary to provide an accumulation of strip prior to the entry of the strip into the processing equipment. In coating operations, if the speed through the coating equipment is slowed down to a great extent, a non-uniform coating and otherwise defective strip is obtained.

Various means have been used to accumulate strip.

In the patent to Rendel, No. 2,306,750, strip is accumulated in a looper pit, the strip being permitted to rest on the bottom of the pit with folds of the strip accumulating one upon another. While this permits a long length of strip to be accumulated, the strip becomes scratched and thus is unsuitable for many purposes.

In the patent to Wells, No. 2,238,667, a double loop is formed in the strip, but there is no means provided for keeping the length of the two loops uniform. There is danger of the strip resting on the bottom of the pit and/or of the majority of strip accumulating in one loop while the other loop practically disappears.

It is an object of my invention to provide a multiple loop control which overcomes the disadvantages of the loops discussed above.

Another object is to provide a loop control which will slow down and stop the feeding means in case the loop becomes dangerously short.

A still further object is to provide a multiple loop control having means for maintaining the lengths of the various loops approximately constant.

These and other objects will be more apparent after referring to the following specification and attached drawings, in which:

Figures 1 and 1A constitute a single figure broken on the line X—X and shows a schematic layout of the multiple loop and the control therefor.

Referring more particularly to the drawings, the reference numerals 2 and 4 indicate looper pits in a continuous processing line. The strip X to be processed, passes between pinch rolls 6 which feed the strip to the pit 2 where a loop 8 is formed. Between the pits 2 and 4 is a second pair of pinch rolls 10 which feed the strip from

the looper pit 2 to the pit 4 where a second loop 12 is formed. A roll 14 located on the outgoing side of the pit 4 supports the strip as it leaves the pit. The strip is then pulled through the processing equipment indicated schematically at 16 by means of the drive bridle rolls 18. The rolls 6, 10 and 18 are rotated by means of conventional shunt field D. C. motors 20, 22 and 24 respectively. While the rolls 6, 10 and 18 are shown as pinch rolls, magnetic feed rolls may be substituted therefor if desired. For example, in high speed lines handling wide light gage, annealed and soft coated products, pinch rolls should be avoided since they act as screws, eventually shifting the material on the rolls until the edges foul and are damaged against the housings of the pinch roll stands or against side guides which are provided on the entry side of the feed rolls. Located in pit 2 are four photoelectric cells or other light responsive devices 26, 28, 30 and 32. Similar photoelectric cells 34, 36, 38 and 40 are located in pit 4. The pits are provided with light sources 42, 44, 46, 48, 50, 52, 54 and 56, which provide the light necessary to energize the respective photoelectric cells, one light being located opposite each photoelectric cell. The photoelectric cells in the loop pits cause relays to function to increase or decrease the speed of the motors 20, 22, and 24 by varying the field resistances.

30 The operation of the loop control is as follows: The strip X is threaded through the rolls 6 and 10, the processing equipment 16 and the drive rolls 18; the loops 8 and 12 being close to the tops of the pits 2 and 4. The starting switch 58 is then operated manually to admit control current to the relay 60, closing the main line contactors 62. The circuit from the control lines 64, 65 to the coil 60 is completed through lines 66, 68, closed contact 70, closed switch 58, and line 72. Closing 35 of the main line contactors 62 provides power to motor 20 from the power lines 74 and 75 through lines 76 and 78 having normally closed contacts 80 therein. Power is provided to motors 22 and 24 through lines 81, 82 and 84, 86 respectively.

40 Hand adjustments on field control rheostats 88 and 90 for motors 20 and 22, respectively, are set so that the motors feed the strip into the pits 2 and 4 slightly faster than motor 24 draws the strip out. When the loops interrupt the light beams of circuits 4a and 4b, the coils of relays 92 and 94 are de-energized causing their respective contacts to open. When both of these contacts are open, the operating coil of relay 96 is de-energized, opening its contact which in turn 45 causes a motor controller 98 to start the reversi-

ble motor 100 of the rheostat 102. This increases the resistance in the field circuit 104, 105 and thereby speeds up all three motors 20, 22 and 24. Adjustable rheostats 106 and 108 in the field circuit of motors 20 and 22, respectively, are set so that these motors feed strip into the pits faster than the motor 24 draws it out. The speed of motor 24 may be adjusted by changing the setting of the variable resistance 110. With motors 20 and 22 operating at a faster rate than motor 24, loops 8 and 12 continue to lower until they interrupt the light beams of circuits 1a and 1b. This de-energizes the coils of relays 112 and 114, respectively, causing their contacts to close and closing the circuits to the coils of relays 116 and 118, respectively, which cuts out the upper portions of the variable resistances 106 and 108, increasing the field current flowing to motors 20 and 22 and slowing them down slightly. Loops 8 and 12 continue to lower slowly until the light beams of circuits 2a and 2b are interrupted. This de-energizes the coils of relays 120 and 122, respectively, causing their contacts to close and completing the circuit to the coils of relays 124 and 126. Energization of the coils closes the contacts of relays 124 and 126, this cutting out more of the resistance of adjustable resistances 106 and 108 and further increases the field current of motors 20 and 22 which lowers their respective speeds. The two portions of the resistance 106 and 108 which are cut out as described above are adjustable and are set by hand to obtain the correct relative speeds of the motors 20 and 22. These adjustments are such that the loop normally remains below the light beam of circuits 2a and 2b. In case the loops 8 and 12 should go lower due to slight maladjustment of the resistances or other factors they will interrupt light circuits 3a and 3b, de-energizing the coils of relays 128 and 130 respectively, causing their contacts to close, which closes the contacts of relays 132 and 134 to short circuit resistances 88 and 90. This increases the field current of motors 20 and 22 respectively, further slowing them down. Any suitable amplifier 135 may be used in the photoelectric circuits to amplify the current generated by the photoelectric tubes. It will be understood that the control for the loop 8 will operate independently of the control for loop 12, but that control of one loop must necessarily change the length of the other loop, which in turn will bring the control for the second loop into operation. When the loops are decreasing in length, their respective controls will operate in the reverse manner, thus speeding up the respective motors. The relative speeds of the motors are so set that during normal operation of the line, loops 8 and 12 will seek the position shown in full lines and will maintain this position in the absence of unusual circumstances.

In case either loop 8 or 12 rises so high in the pits that circuits 4a or 4b are completed, the coil of relays 92 or 94 will be energized, closing its contact. Closing of contact 92 completes the circuit to the coil of relay 96 through lines 66, 136 and 72. Closing of the contact of relay 94 completes the circuit to the coil of relay 96 through lines 66, 136 and 138. Energization of the coil of relay 96 closes its contacts and completes the circuit to motor controller 98, which decreases the resistance of motor operated rheostat 102. This in turn increases the field current to motors 20, 22 and 24, slowing them down so that the processing line can be stopped readily without excessive drifting. Located near the top of pits 2 and 4 are

limit switches 140 and 142 arranged in series. Each of the switches has an arm 143 extending into the respective loops and adapted to be actuated thereby to open the switch when the loop rises close to the top of the pit. Opening of either switch 140 or 142 breaks the circuit to the stop relay 70, which in turn opens the circuit to the main line relay 60, opening the switches 62 and stopping all motors. Suitable brakes may be used to stop the motor quickly when the power is shut off. These slow down and stop circuits prevent possible damage to the equipment or breaking of the strip in case the other controls do not operate properly, or in case of delays during welding.

When it is necessary to stop the pinch rolls 6 to weld a succeeding coil of strip to the tail end of strip X the operator closes switch 144. This completes the circuit to the coil of relay 96 through line 146, the coil of relay 148, line 150, the coil 152, lines 136, 66. Closing of the contacts of relay 96 completes the circuit to motor controller 98, which decreases the resistance of motor operated rheostat 102 to slow down motors 22 and 24. Energization of coil 152 opens contacts 80 and stops motor 20. Energization of the coil of relay 148 opens its contacts and places the variable resistance 110 in the field circuit of motor 24, this causing the motor 24 to operate at twice the speed of motor 22. For example, the normal speed of the line may be 600 feet per minute. If the amount of available loop in the pits is 90 feet and the time interval required for making a weld or otherwise fastening the strips together is 15 seconds, the motor 24 must be slowed down to a speed of 360 feet per minute. Motor 20 is stopped and in order for both loops 8 and 12 to be used simultaneously, motor 22 must drive the rolls 10 at half the speed or 180 feet per minute. The proper motor speeds under any particular conditions are obtained by adjusting the various resistances shown to obtain the required field current of the motors once set for a particular condition, these resistances are not changed. For normal starting of the line, the starting switch 58 is used. In case limit switches 140 or 142 have stopped the line, it is necessary to use the starting switch 154.

If desired, any number of loops may be provided with similar operating mechanism. If more than two loops are used, the speeds of the various motors will be so adjusted during welding that the loops will be used simultaneously. In all cases the speed of motor 22 will be equal to the speed of motor 24 divided by the number of loops and the speed of each motor will be equal to the speed of the next preceding motor plus the speed of motor 22.

While one embodiment of the invention has been shown and described, it will be more apparent that other adaptations and modifications may be made without departing from the scope of the following claims.

I claim:

1. Strip handling apparatus comprising means for forming a multiple loop in said strip, individual means for feeding strip to each of said loops at variable speeds, means for feeding the strip from the last of said loops, means responsive to the position of each of said loops for varying the speed of their respective feeding means, means for stopping the feeding of the strip to the first loop and means responsive to said last named means for causing the feeding means to the succeeding loops to operate at a

lower rate of speed than the next succeeding feeding means.

2. Strip handling apparatus comprising means for forming a multiple loop in said strip, individual means for feeding strip to each of said loops at variable speeds, means for feeding the strip from the last of said loops, means responsive to the position of each of said loops for varying the speed of their respective feeding means, means for stopping the feeding of the strip to the first loop, means responsive to said last named means for causing the feeding means to the succeeding loops to operate at a lower rate of speed than the next succeeding feeding means, and means to stop said feeding means when any of said loops reaches a given height.

3. Strip handling apparatus comprising means for forming a multiple loop in said strip, individual means for feeding strip to each of said loops at variable speeds, means for feeding the strip from the last of said loops, a light responsive device for each loop adapted to speed up the respective feeding means as the loop controlled thereby decreases in length and to slow up the feeding means as the loop increases in length, means for stopping the feeding of the strip to the first loop and means responsive to said last named means for causing the feeding means to the succeeding loops to operate at a lower rate of speed than the next succeeding feeding means.

4. Strip handling apparatus comprising means for forming a multiple loop in said strip, individual means for feeding strip to each of said loops at variable speeds, means for feeding the strip from the last of said loops, a light responsive device for each loop adapted to speed up the respective feeding means as the loop controlled thereby decreases in length and to slow up the feeding means as the loop increases in length, means for stopping the feeding of the strip to the first loop, means responsive to said last named means for causing the feeding means to the succeeding loops to operate at a lower rate of speed than the next succeeding feeding means, and means to stop said feeding means when any of said loops reaches a given height.

5. Strip handling apparatus comprising means for forming a multiple loop in said strip, a variable speed feed roll for each of said loops, means for feeding the strip from the last of said loops, a plurality of light responsive devices located at different levels of each loop, the lower devices being adapted to speed up their respective feed rolls as the loop controlled thereby decreases in length and to slow up the last named rolls as the loops increase in length, the highest of said devices being adapted to slow down their respective feed rolls as the loop controlled thereby decreases in length and to speed up the last named rolls as the loops increase in length, means for stopping the feeding of the strip to the first loop and means responsive to said last named means for causing the feed rolls for the succeeding loops to operate at a lower rate of speed than the next succeeding feed roll.

6. Strip handling apparatus comprising means for forming a multiple loop in said strip, a variable speed feed roll for each of said loops, means for feeding the strip from the last of said loops, a plurality of light responsive devices located at different levels of each loop, the lower devices being adapted to speed up their respective feed rolls as the loop controlled thereby decreases in length and to slow up the last named rolls as the loops increase in length, the highest of said de-

vices being adapted to slow down their respective feed rolls as the loop controlled thereby decreases in length and to speed up the last named rolls as the loops increase in length, means for stopping the feeding of the strip to the first loop, means responsive to said last named means for causing the feed rolls for the succeeding loops to operate at a lower rate of speed than the next succeeding feed roll, and means to stop said feed rolls when any of said loops reaches a given height.

7. Strip handling apparatus comprising means for forming a multiple loop in said strip, a motor driven feed roll for each loop, a motor driven roll for feeding the strip from the last of said loops, a light responsive device for each loop adapted to speed up the respective feed roll as the loop controlled thereby decreases in length and to slow up the feed roll as the loop increases in length, said first named rolls normally operating at approximately the same lineal speeds, means for stopping the feeding of the strip to the first loop and means responsive to said last named means for causing the feed rolls for the succeeding loops to operate at a lower rate of speed than the next succeeding feed roll.

8. Strip handling apparatus comprising means for forming a multiple loop in said strip, a motor driven feed roll for each loop, a motor driven roll for feeding the strip from the last of said loops, a light responsive device for each loop adapted to speed up the respective feed roll as the loop controlled thereby decreases in length and to slow up the feed roll as the loop increases in length, said first named rolls normally operating at approximately the same lineal speeds, means for stopping the feeding of the strip to the first loop, means responsive to said last named means for causing the feed rolls for the succeeding loops to operate at a lower rate of speed than the next succeeding feeding means, and means to stop said feed rolls when any of said loops reaches a given height.

9. Strip handling apparatus comprising means for forming a multiple loop in said strip, a motor driven feed roll for each loop, said rolls normally operating at approximately the same lineal speeds, a motor driven roll for feeding the strip from the last of said loops, a plurality of light responsive devices located at different levels of each loop, the lower devices being adapted to speed up their respective feed rolls as the loop controlled thereby decreases in length and to slow up the last named rolls as the loops increase in length, the highest of said devices being adapted to slow down their respective feed rolls as the loop controlled thereby decreases in length and to speed up the last named rolls as the loops increase in length, means for stopping the feeding of the strip to the first loop and means responsive to said last named means for causing the feed rolls for the succeeding loops to operate at a lower rate of speed than the next succeeding feed rolls.

10. Strip handling apparatus comprising means for forming a double loop in said strip, a motor driven roll for feeding the strip to the first of said loops, a second motor driven roll for feeding the strip from the first to the second loop, a third motor driven roll for feeding the strip from said second loop, said rolls normally operating at approximately the same speeds, a plurality of light responsive devices located at different levels of each loop, the lower devices being adapted to speed up their respective feed rolls as the loop controlled thereby decreases in length and to slow

up the last named rolls as the loops increase in length, the highest of said devices being adapted to slow down their respective feed rolls as the loop controlled thereby decreases in length and to speed up the last named rolls as the loops increase in length, means to stop said motors when either of said loops reaches a given height, means for stopping the rotation of said first roll, and means responsive to said last named means for causing the second feed roll to operate at approximately one-half the speed of the third roll.

11. Strip handling apparatus comprising means for forming a loop in said strip, means for feeding strip to said loop at variable speeds, means for feeding strip from said loop, a plurality of light responsive devices located at different levels of the loop, the lower device being adapted to speed up its feeding means as the loop decreases in length and to slow up the feeding means as the loop increases in length, the highest of said devices being adapted to slow down its feeding means as the loop decreases in length and to speed up the feeding means as the loop increases in length, means for stopping the feeding of the strip to the loop and means responsive to said last named means for slowing down the means for feeding strip from said loop.

12. Strip handling apparatus comprising means for forming a multiple loop in said strip, individual means for feeding strip to each of said loops at variable speeds, means for feeding the strip from the last of said loops, means for stopping the feeding of the strip to the first loop, and means responsive to said last named means for decreasing the rate of feed to each of the succeeding loops, the feed to each loop being decreased less than the feed to the next succeeding loop.

13. Strip handling apparatus comprising means for forming a multiple loop in said strip, individual means for feeding strip to each of said loops at variable speeds, means for feeding the strip from the last of said loops, means responsive to the position of each of said loops for varying the speed of their respective feeding means, means for stopping the feeding of the strip to the

first loop, and means responsive to said last named means for changing the rate of feed to at least one of the succeeding loops.

14. Strip handling apparatus comprising means for forming a multiple loop in said strip, individual means for feeding strip to each of said loops at variable speeds, means for feeding the strip from the last of said loops, means for stopping the feeding of the strip to the first loop, and means for decreasing the rate of feed to each of the succeeding loops after stopping feeding of the strip to the first loop, the feed to each loop being decreased less than the feed to the next succeeding loop.

15. Strip handling apparatus comprising means for forming a multiple loop in said strip, individual means for feeding strip to each of said loops at variable speeds, means for feeding the strip from the last of said loops, means responsive to the position of each of said loops for varying the speed of their respective feeding means, means for stopping the feeding of the strip to the first loop, and means for changing the rate of feed to at least one of the succeeding loops after stopping feeding of the strip to the first loop.

16. Strip handling apparatus comprising means for forming a loop in said strip, means for feeding strip to said loop at variable speeds, means for feeding the strip from said loop, means responsive to the position of said loop for varying the speed of its feeding means, means for stopping the feeding of the strip to the loop, and means responsive to said last named means for slowing down the means for feeding strip from said loop.
